UNITED STATES PATENT OFFICE.

FORDYCE A. LYMAN, OF CLEVELAND, OHIO.

VAPOR-BURNER.

SPECIFICATION forming part of Letters Patent No. 225,067, dated March 2, 1880.

Application filed May 31, 1879.

To all whom it may concern:

Be it known that I, FORDYCE A. LYMAN, of Cleveland, in the county of Cuyahoga and State of Ohio, have invented certain new and useful Improvements in Vapor-Burners; and I do hereby declare the following to be a full, clear, and exact description of the invention, such as will enable others skilled in the art to which it pertains to make and use it, reference being had to the accompanying drawings, which form part of this specification.

My invention relates to vapor-stoves; and it consists in a construction hereinafter described and claimed.

15 In the drawings, Figure 1 is an elevation of a device embodying my invention. Fig. 2 is a sectional view on a plane passed through the vaporizing-chamber and at right angles to the feed-pipe. Fig. 3 is a separate view of the 20 burner. Fig. 4 is a detail plan view of the cup-shaped support and the burner.

A is a feed-pipe leading from the oil-reservoir to the vaporizing-chamber B. The vaporizing-chamber B is provided with the needle-valve rod C, which passes through a suitable stuffing-box at D. The upper extremity of this valve-rod is screw-threaded; and engages with a screw-threaded eye-bearing, E, which latter is perforated for the passage of vapor 30 to the jet-orifice.

F is the top of the stove, made in any suitable form for supporting the vessel or article to be heated. G is a cup-shaped support for the burner H. This merely rests upon the open-worked bottom of the cup-shaped support G, and said bottom is formed with an opening, c, through which the vapor from the vapor-jet enters the burner.

The burner H is suitably perforated, so that 40 the mixture of vapor and air may emerge therefrom and be burned.

The lower portion of the burner is provided with lateral lugs h, which project inwardly therefrom, and have end bearing against the 45 annual projection f, formed about the vapor-opening in the open-worked bottom of the cup-shaped support. These lugs maintain said burner in position within said support G.

The form of construction shown in the drawings consists of depending arms L, secured to the under side of the stove-top, and having horizontal inwardly-projecting flanges a, on 50 which loosely rests the cup-shaped support G.

The burner H is formed with a fluted or serrated top edge, b.

Heretofore, among other forms of vapor-stoves, a burner has been supported below the stove-top, and hence my invention does not cover the broad principle of so locating a burner, but covers means substantially the same as those hereinafter claimed, by which I accomplish this result.

The operation of this device is as follows: Oil having been introduced through the tubes A and B, it is permitted to flow out through the subheating-jets, and, being lighted, raises the temperature of the vaporizing-chamber to a vaporizing heat. This flame will then be governed to burn with greater or less freedom and generate vapor with greater or less rapidity. The needle-valve may be then opened. The jet from the jet-orifice will then rise in an exactly central line, drawing with it the adjacent air. The vapor-jet and the air being thus commingled within the burner H, the resulting flame will be found to be almost perfectly blue and the combustion perfect.

In order to prevent fluctuations of the flame, I propose to fill the chamber B, to a greater or less extent, with iron chippings or their equivalent.

What I claim is—

1. The combination, with a cup-shaped support whose bottom is provided with openings, of arms which depend from the stove-top and maintain the cup-shaped support in position, together with a burner located within said support and resting on its open-work bottom, substantially as set forth.

2. The combination, with a stove-top and depending arms secured thereto, of a cup-shaped support held by said arms, and whose open-worked bottom has an annular projection formed about its vapor-opening, together with a burner, which rests within said support and is provided with lateral lugs having end bearings against said annular projection, substantially as set forth.

In testimony whereof I have signed my name to this specification in the presence of two subscribing witnesses.

FORDYCE A. LYMAN.
